US00D866446S

(12) **United States Design Patent** (10) **Patent No.:** **US D866,446 S**
Chen (45) **Date of Patent:** **** Nov. 12, 2019**

(54) **CONNECTOR FOR AUTOMOBILE**

(71) Applicant: **Xiuying Chen**, Zhejiang (CN)

(72) Inventor: **Xiuying Chen**, Zhejiang (CN)

(73) Assignee: **Zhejiang Shijia Import and Export Co., Ltd**, Pinghu, Zhejiang (CN)

(**) Term: **15 Years**

(21) Appl. No.: **29/676,295**

(22) Filed: **Jan. 10, 2019**

(51) LOC (12) Cl. **12-16**

(52) U.S. Cl.

USPC **D12/400**

(58) **Field of Classification Search**

USPC D12/400; D13/133, 134, 137, 147, 154

See application file for complete search history.

(57) **CLAIM**

The ornamental design for a connector for automobile, as shown and described.

DESCRIPTION

FIG. 1 is a top, front and right side perspective view of a connector for automobile showing my new design;
FIG. 2 is a top, rear and left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
The broken lines in the figures depict portions of the article which form no part of the claimed design.
